UNITED STATES PATENT OFFICE

124,509

DESIGN FOR AN EVENING GOWN ENSEMBLE OR SIMILAR ARTICLE

Karen Stark, New York, N. Y.

Application September 20, 1940, Serial No. 95,232

Term of patent 3½ years

To all whom it may concern:

Be it known that I, Karen Stark, a citizen of the United States, residing at Hyde Park Hotel, New York city, in the county of New York and State of New York, have invented a new, original, and ornamental Design for an Evening Gown Ensemble or Similar Article, of which the following is a specification, reference being had to the accompanying drawing, forming part thereof.

The decorative elements on the jacket member of the ensemble and the trimming on the dress member are comprised of gold embroidery.

I claim:

The ornamental design for an evening gown ensemble or similar article, substantially as shown and described.

KAREN STARK.
